LIFTING JACK

Filed Dec. 20, 1926

INVENTOR
WALTER W. MATTHES

BY
Richard J. Cook
ATTORNEY

UNITED STATES PATENT OFFICE.

WALTER W. MATTHES, OF WELLINGTON, WASHINGTON.

LIFTING JACK.

Application filed December 20, 1926. Serial No. 155,938.

This invention relates to improvements in lifting jacks, and particularly to jacks of that character designed especially for removing and replacing the brasses in the journal boxes of freight, passenger or other railway cars, it being the principal object of this invention to provide a re-brassing jack that may be used for this purpose without requiring any special blocking as a foundation for supporting the jack in use.

More specifically stated, the invention resides in the provision of a jack for the above purpose having its housing, or base portion, provided with a lateral shoulder adapted for supporting contact upon the rim formed about the periphery of the car wheel in close proximity to the tread.

A further object of the invention is to provide the jack with means adapted to be extended into contact, or abutment, with the rail on which the car wheel rests, so as to serve as a means for preventing movement of the journal box outwardly along the axle when lifting pressure is exerted by the jack against it.

A still further object of the invention is to provide the jack head with means for retaining it against slipping and properly in holding contact with the journal box during use.

Other objects of the invention reside in the various details of construction and combination of parts whereby a substantial and efficient jack will be provided at a relatively small cost.

In accomplishing these and other objects of the invention, I have provided the improved details of construction the preferred forms of which are illustrated in the accompanying drawings, wherein—

Figure 1 is a view showing a jack embodied by the present invention as applied in use to the wheel and journal box of an ordinary type of railway car; the box and wheel being shown in vertical section for better illustration.

Figure 2 is a central vertical section of the jack.

Figure 3 is a horizontal section taken on the line 3—3 in Figure 2.

Figure 4 is an inner side elevation of the jack.

Figure 5 is a detail view showing the application of the jack head to journal boxes of that type equipped with tie bars.

Referring more in detail to the drawings—

1 designates the casing, or housing, of the jack; this being somewhat cylindrical in form and having an integrally formed, laterally projecting shoulder 2 at one side, with a slightly inclined under surface 3 to which a toothed bearing plate 4 is fixed by bolts, or the like, as indicated at 5. Slidably contained within the jack housing and extending from the upper end thereof, is a lifting post 6. This is keyed against rotation in the housing, as indicated at 7, and is provided at its upper end with a shoe or head 8 adapted to engage with the journal box, and within the housing it is threaded, as at 9, onto a screw 10 that is revolvably supported at its lower end through the intermediacy of anti-friction bearings 11 upon the closed lower end or base of the jack housing. Encircling the lower end of the screw and fixed thereto, is a bevel gear 12 that meshes with a driving bevel gear wheel 13 that is fixed on a shaft 14 extending horizontally within the casing and which, at its outer end, has a ratchet wheel 15 fixed thereon. A hand lever 16 is pivotally mounted on the outer end of the shaft 14 and this carries a pivotally mounted, spring pressed pawl 17, by means of which, up and down movement of the hand lever will impart rotative movement to the ratchet and shaft to rotate the gears in such manner as to cause the lifting post to be extended.

For the purpose of bracing the jack when it is in use as a means of preventing outward tilting of its upper end when lifting pressure is applied and which will be caused by the offset relation of the shoulder 2 with respect to the axial line of the post 6, I have provided a horizontal bore 18 in the base of the jack housing, and, in this bore, have slidably keyed a pin 19. This pin is adapted to project from the jack housing at a point directly below the shoulder 2 and it may be extended, as presently described, into contact with the vertical web of the rail on which the wheel rests. Threaded into the inner end of the pin, is a screw 20 that is revolvably fixed in the housing and which is provided at its outer end with a wrench head 21 whereby it may be rotated for the purpose of extending or retracting the pin.

It is preferred that the outer end portion of the hand lever 16 be disconnectible from within a socket in the mounting head, or end portion, designated at 16', and provided with a wrench socket, as at 22, applicable to the

head 21 so that no special wrench need be provided for the purpose of adjusting the screw 20.

When the jack is to be put in use, the shoulered portion 2 of the housing is first seated upon the projecting rim 24 of the car wheel 25 at a point directly below the axle 26; the teeth of the bearing plate 4 that is secured to the shoulder being so constructed as to preclude any possibility of the shoulder slipping off the flange as pressure is applied. The lifting post 6 is then extended upwardly by manipulation of the handle 16 to bring the shoe 8 against the under side of the journal box 29, as shown in Figure 1. In order that the shoe may not slip outwardly, I have provided it with a transverse groove 30 in which a latch plate 31 is pivotally mounted by a horizontally extending pin 32 through the shoe. The latch has an upstanding foot 33 at one end that is adapted, when the latch is in use, to engage with the rear edge of the journal box, as in Figure 1.

It will be stated here that in certain types of construction, the journal boxes of a truck are connected across the top and bottom by arch bars. Some of these bars are quite wide and are in such position that the jack could not be set perpendicularly in use without the head 8 overlapping the bottom bar. In order to facilitate the use of the jack with cars of this latter construction, the upper surface of the head is cut down at one side, providing a vertical shoulder 27 for engaging the edge of the bottom tie bar, as shown in Figure 5. This prevents the jack head slipping outwardly and affords a good bearing for it. The latch 31 is not required when the jack is used with boxes so equipped but is reversed 40 in its position by swinging it about its pivot pin, so that it will lie within the groove with the foot extending downwardly.

After the jack has been properly positioned on the car wheel flange and the shoe and lifting post extended against the journal box by manipulation of the handle 16, the pin 19 is extended into contact with the rail web. The hand lever is then manipulated to extend the lifting post to jack up the journal box sufficiently that the brass, or bushing, as indicated at 40 in Figure 1, will be lifted from the axle and may be removed and replaced.

While the jack here shown has been designed with a shoulder at one side and is adapted for use in a certain way, it is readily apparent that this construction does not prevent its use in the ordinary way for any other jacking purpose, since, if it is not desired to support the jack in use from the car wheel flange, it may be seated on any suitable blocking and used as the ordinary lifting jack is now used.

This invention provides for a very simple

and efficient jack, for the purpose specified and requires no blocking or preparing of any supporting foundation and, in this way, greatly facilitates the work for which it is intended.

It is to be understood that the details of construction of the jack mechanism; that is, the means whereby the lifting post is extended or retracted, can be of any suitable construction and may be changed or varied to meet any requirements necessary.

Having thus described my invention, what I claim as new therein and desire to secure by Letters-Patent, is:

1. A re-brassing jack of the character described comprising a jack base housing provided at one side with a laterally extending shoulder adapted to rest upon the rim flange of the car wheel to support the jack in use, a lifting post extendible from the jack housing having a shoe at its upper end adapted to seat against a journal box, said shoe being provided with a transverse groove, a latch plate pivotally mounted in the groove to lie flush with the top of the shoe and having a laterally turned foot at one end adapted, when the latch is in functional position, to engage with the end of the journal box to prevent outward slipping of the shoe.

2. A re-brassing jack of the character described comprising a base housing provided at one side with a laterally extending shoulder adapted to rest upon the rim flange of a car wheel to support the jack in use, a lifting post extendible from the jack having a shoe at its upper end adapted to seat against a journal box, said jack housing having a horizontal bore in its lower end, a pin slidably keyed in the bore, a screw revolvably fixed in the bore and threaded into the pin and having a head exteriorly of the housing, whereby it may be rotated to extend the pin into contact with the web of a rail on which the car wheel rests to prevent outward tilting of the upper end of the jack in use.

3. A re-brassing jack of the character described comprising a base housing provided with a laterally extending shoulder at one side having a toothed plate fixed thereto adapted for supporting contact upon the rim flange of a car wheel, a lifting post extendible from the jack provided with a shoe at its upper end adapted to seat against a journal box, means on the shoe for preventing outward slippage, a pin slidably keyed in the lower end of the jack housing and an adjusting screw connected with the pin operable to extend it into holding contact with the web of the rail on which the car wheel rests for the purpose set forth.

Signed at Cascade Tunnel, Washington, this 30th day of November, 1926.

WALTER W. MATTHES.
